UNITED STATES PATENT OFFICE.

LOUISE TULLY, OF NEW YORK, N. Y., ASSIGNOR TO THE BUTTERICK PUBLISHING COMPANY, (LIMITED,) OF SAME PLACE.

DESIGN FOR A LADY'S WALKING-SKIRT.

SPECIFICATION forming part of Design No. 14,500, dated December 18, 1883.

Application filed October 27, 1883. Term of patent 3½ years.

To all whom it may concern:

Be it known that I, LOUISE TULLY, of the city, county, and State of New York, have invented and produced a new and original

5 Design for a Pattern of a Lady's Walking-Skirt, (numbered 8,939;) and I do hereby declare that the engraved prints accompanying this specification convey to any one accustomed to using paper patterns a clear under-
10 standing of how a garment made up by the pattern will appear.

The design shows a short walking-skirt, a tablier drapery that exhibits plaits at the side

edges and falls over the top of a pointed drapery of triple box-plaits, and a deep full back 15 drapery that is draped by plaits at the center and side edges.

What I claim as my invention, and desire to secure by Letters Patent, is—

The design for a lady's walking-skirt, as 20 shown in the engraved prints accompanying this specification.

LOUISE TULLY.
